UNITED STATES PATENT OFFICE

2,575,610

FLIGHT CONVEYER

Charles F. Ball, Franklin, Pa., assignor to Joy
Manufacturing Company, a corporation of
Pennsylvania

Application December 27, 1947, Serial No. 794,136

4 Claims. (Cl. 198—175)

1

This invention relates to flight conveyors, and more particularly to flight conveyors which are especially adapted for use in shuttle cars.

Shuttle cars are now used widely in mines to haul mined material, such as coal, ores and the like, from a working area of a mine to some point of delivery, either terminal or intermediate, and these shuttle cars generally include body portions and discharge sections which are pivotally connected together and which have flight conveyors extending along their bottoms for moving the material which is loaded into the car out through the discharge section when the desired point of discharge has been reached. These flight conveyors generally are in the form of a continuous flexible conveyor which has an active strand that extends throughout the bottom of the car and of the discharge section, the conveyor being usually driven at the outer end of the discharge section by appropriate means, and the conveyor also comprises a run which passes beneath the bottom of the discharge section and the bottom of the main car body and around an idler at the end of the car remote from the discharge section. Due to the weight of the material with which the car is loaded, much of which weight rests directly on the conveyor, a rugged construction is necessary, and in order that the material may be well cleaned up in the car and that the conveyor may have a minimum tendency to have material work beneath it and lift it above the car bottom, it is desirable that provision be made for assuring the movement of the flights in scraping relation to the car bottom and the bottom of the discharge section. Desirably, in shuttle cars, there will be spaced flight-moving chains, and flight elements will be extended transversely of the bottom portions of the shuttle car body and its discharge section and be secured to the actuating chains by connections allowing for limited movements of the flights angularly relative to the chains.

Where the conveyor must handle heavy material, for example, large lumps of coal, limestone or iron ore, there is a tremendous hammering as the load is dropped into the conveyor—as from a loading machine. Also, of course, there is considerable twisting and jerking when the shuttle car load is set in motion preliminary to discharge, and during its discharge movement. Accordingly, a non-rigid connection is desirable, because it leaves the chain relatively free to respond to the several forces acting on it; and by loosely attaching the flights, as through rectangular extremities received in slightly larger rectangular

2

holes in the side chains, or otherwise, to such side chains, the flights not only can, but do, rock or tilt; and by arranging the projections so that their central horizontal plane is above the central horizontal plane of the flight as a whole, there will be provided the possibility, and the actuality, of a forward tilt of the flights, with the result that the leading edges, through friction drag upon the bottom of the body and discharge section of the shuttle car, will be caused to provide a scraping or wiping action over the latter, thus insuring a most efficient and complete discharge of the material from the shuttle car. While the foregoing discussion relates particularly to the employment of the invention in shuttle cars, its use is by no means so limited, and it has a wide applicability to other conveying purposes and devices.

20 An object of the invention is to provide an improved chain and flight conveyor. Another object of the invention is to provide an improved flight for a chain and flight conveyor. A further object of the invention is to provide an improved chain and flight conveyor of a construction which will provide a very effective wiping or scraping action of the flights along the surfaces over which they are to move material. Still another object of the invention is to provide an improved pivotal connection between the flights of a chain and flight conveyor and the chains proper thereof. Other objects and advantages of the invention will hereinafter more fully appear.

The invention is illustrated in the accompanying drawing, and of which:

25 Fig. 1 is a plan view of a flight conveyor chain incorporating the invention.

Fig. 2 is an enlarged view, in part on the plane of the vertical section line 2—2 of Fig. 1, and in part in elevation, of a portion of a conveyor flight and one of the associated drive chains.

30 Fig. 3 is an enlarged longitudinal, vertical section on the plane of the line 3—3 of Fig. 2 showing a flight in cross section and showing its pivot mounting in broken lines.

35 Fig. 4 is an enlarged perspective view of a flight and of one link of a conveyor chain with which the flight is adapted to be associated and by which the flight is adapted to be propelled.

40 For the purposes of this application, it is unnecessary to illustrate the structure of the shuttle car or other device with which the chain and flight conveyor disclosed may be employed, and it will suffice to say that there is shown at 1 in Figs. 45 2 and 3 a surface over which a chain and flight

conveyor 2 is adapted to travel and to move material. This chain and flight conveyor includes side chains 3 and 4, and flights 5 extending between the side chains. The flights 5 are shown as being solid in cross section as at 6, but it will be obvious that they may be made hollow, if desired. They desirably have relatively flat lower surfaces, and are shown in Fig. 3 as approximately rectangular in cross section, having their longer sides relatively parallel to the surface 1. They may obviously be of other cross sections. They are connected to the side chains for tilting or pivotal movement about axes extending longitudinally of said flights above the mid-points between the tops and bottoms thereof. They have, as shown, projecting pivot portions 8 at either end. These may vary in shape but are shown as being non-circular in cross section, and similar in cross section to the flights proper, but smaller than the flights. They are so arranged that the intersection of median, horizontal and vertical planes extending longitudinally of the pivot portions is at a point (or line) 10 which is well above the point (or line) of intersection of median horizontal and vertical planes extending longitudinally of the flights as a whole.

The chains 3 and 4 are made up of links 11 and 12 connected by pins 13, extending through spacing sleeves 14 surrounded by outer wear sleeves 15. The links 11 at the mutually adjacent sides of the chains 3 and 4 each have opening 16 in them, these openings being desirably, with the construction illustrated, approximately equally spaced with respect to the top and bottom of the chains 3 and 4, and slightly larger, both vertically and also longitudinally of the chains, than the projections 8. The openings 16 are also non-circular and are similar in shape to the projections 8; in the embodiment shown the openings are rectangular. Thus there is permitted a small degree of tilt of the flights through the loose fit of their projecting portions 8 in the openings 16. The positions of the projections 8 relative to the bodies of the flights and of the openings 16 relative to the links 11 may be such that when the flights are not in motion their bottom surfaces may rest upon the surface 1 in flat contact with the latter, but during driven movement of the chain and flight conveyor there may be a slight lifting of the rearward edges of the flights, as at 17 in Fig. 3, while the forward lower corners 18 wipe or scrape over the surface 1.

It will be understood that in use the tops of the flights 5, and also of the chains 3 and 4, may be covered to a depth of some feet by heavy material. This material will not only rest on the tops of the flights, but it will also rest between the flights on the surface 1. When it is necessary to start the flight conveyor to effect movement of the material, e. g. its discharge from a shuttle car, and the chains are moved towards the left in Fig. 1, it will be appreciated that the flights will, to a certain degree, as it were, trip on the material resting on the bottom 1 and be tilted somewhat in the manner shown in Fig. 3, so as to wipe, as at their forward lower corners 18, over the bottom surface 1. There will thus be a definite scraper action of the flights, and because of the low height of the flights and the disposition of their pivots with respect to the links 11 of the chains 3 and 4 there will be accomplished a very effective cleaning action of the shuttle car bodies and discharge sections. It will be understood that the projecting portions 8 need not be wholly below the tops of the flights 5, but may be disposed in various positions and

constructed in various ways so as to secure the tripping and scraping actions mentioned.

Not only will the construction described effectively move the material along and clear the material off the surface 1, but, through the inherent flexibility, breakage of the chains, either under the pounding of material loaded onto the conveyor, or by reason of the strains imposed in getting the mass of material into motion and maintaining it in motion during discharge, will be avoided. The pivotal connections of the flights to the chains so that they tend to tilt forwardly when in normal use, and the nature of the pivotal connections which prevent such freedom of motion as to permit inversion of the flights, are obviously desirable elements in my invention, from different aspects thereof.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, in a flight conveyor, a pair of chains having in certain links thereof polygonal openings, and conveyor flights having projections from their ends received in said openings and disposed with their longitudinal centers above the longitudinal centers of said flights, said projections also being polygonal and of smaller dimension on each side thereof than said openings.

2. In combination, in a flight conveyor, a pair of chains having in certain links thereof rectangular openings, and conveyor flights having projections from their ends received in said openings and disposed with their longitudinal centers above the longitudinal centers of said flights, said projections also being rectangular and of smaller dimension on each side thereof than the corresponding sides of said openings.

3. In combination, in a chain and flight conveyor, a pair of chains comprising sets of parallel links, certain of said links at the mutually closer sides of said chains having openings therein for the reception of flight pivots, and conveyor flight elements having longitudinally projecting ends forming pivots and received in said openings, said pivots and said openings formed to permit limited tilting of said flight elements about longitudinal axes, the pivots being so arranged on the flights that the intersection of median horizontal and vertical planes extending longitudinally of the pivots is above the intersection of median horizontal and vertical planes extending longitudinally of the flights as a whole, to cause the reactions on said elements of material moved by them to press their lower forward portions downward.

4. In combination, in a chain and flight conveyor, side chains, and transverse flights engageable with a surface over which material is to be moved, and means for connecting said flights to said chains for tilting movement about axes extending longitudinally of said flights above the mid-points between the tops and bottoms thereof, said means including chain links having non-circular openings, and substantially horizontal projections on the flights of similar shape as but smaller than said openings and having said axes

disposed above the aforesaid mid-points of said flights.
